United States Patent Office

Des. 217,986
Patented July 7, 1970

217,986

RADIO CABINET

Robert W. Becker, Naperville, and David P. Chuboff,
North Barrington, Ill., assignors to Zenith Radio Cor-
poration, Chicago, Ill., a corporation of Delaware

Filed Aug. 18, 1969, Ser. No. 18,738

Term of patent 14 years

Int. Cl. D14—03

U.S. Cl. D56—4

FIG. 1

FIG. 2

FIG. 4

FIG. 3

FIG. 5

FIG. 1 is a frontal, top perspective view of our design for a radio cabinet;

FIG. 2 is a front elevational view thereof;

FIG. 3 is a top view thereof;

FIG. 4 is a cross-sectional view taken along line 4-4 of FIG. 2; and

FIG. 5 is a cross-sectional view taken along line 5-5 of FIG. 4.

The bottom is substantially plain and unornamented. We claim:

The ornamental design for a radio cabinet, substantially as shown and described.
